UNITED STATES PATENT OFFICE.

JOSEPH SCHMITT AND CHARLES L. RUEHS, OF CHICAGO, ILLINOIS, ASSIGNEES OF ONE-THIRD
TO CHARLES SCHLEYER, OF CHICAGO, ILLINOIS.

CARVING-MACHINE.

No. 910,422.

Specification of Letters Patent.

Patented Jan. 19, 1909.

Application filed April 15, 1905. Serial No. 255,699.

To all whom it may concern:

Be it known that we, JOSEPH SCHMITT and CHARLES L. RUEHS, citizens of the United States, residing at Chicago, in the county of 5 Cook and State of Illinois, have invented certain new and useful Improvements in Carving-Machines, of which the following is a specification.

This invention relates to improvements in 10 carving machines of that class in which a number of pieces are simultaneously carved from a single pattern.

The especial object of our improvements is 15 to produce a machine that can be economically built, and will be easy to operate and not liable to get out of order.

A further object is to provide a simple universal movement for such machines so that 20 the cutting tools may be freely and accurately moved in practically any vertical or horizontal plane.

A still further object is to provide a work-holding table supported on springs which are 25 capable of adjustment so as to perfectly balance the weight of the different models and pieces of wood being carved.

A further object is to construct a carving machine that can be hung from a wall instead of supported on the floor, thus saving 30 space and avoiding much of the vibration which interferes with the work of such machines as generally constructed.

Our machine possesses other advantages of 35 construction and operation which will be readily apparent to those skilled in the art and need not be herein specifically referred to.

Referring to the accompanying drawing:— Figure 1 is a front elevation of our improved machine; Fig. 2 is a top plan view of said 40 machine; Fig. 3 is a side elevation of the machine; Fig. 4 is a detail in cross section on an enlarged scale showing anti-frictional bearings used in our machine; Fig. 5 is an 45 elevational view on an enlarged scale showing the anti-frictional bearings employed in our machine, and a portion of the work frame; Fig. 6 is a cross section on the line x—x Fig. 1; Fig. 7 is a side elevation of the tracer carrying arm of the tool-frame; Figs. 50 8 and 9 are details on an enlarged scale of the spring supporting element, and Fig. 10 is a view on an enlarged scale partly in elevation and partly in section of the roller bearings employed in our machine.

55 In its general construction, our machine

involves a bed adapted to be secured to a wall, and to furnish a support for a frame on which are mounted the tracing and cutting tools and the means for driving same, and said frame is vertically adjustable on its support; said machine also includes brackets on which are mounted two sets of guide rails, one set of which is adapted to freely slide transversely on the other. Slidably mounted on one set of guide rails is a frame which carries the pattern and work pieces, and said frame is yieldingly and rockingly supported.

While we have shown a two-cutter machine it will be apparent that the principles of construction adopted in our machine are 70 applicable to a machine having any number of cutters.

Referring to the drawings in detail, A represents a rectangular frame made up of suitable vertical and horizontal plates bolted together and same form the supporting bed of our machine, which is adapted to be bolted to a wall. At the top of the bed, near its corners, and on extensions a^2 , are bolted blocks a^1 , a^1 , in which a shaft a^3 is journaled. 75 On the ends of the shaft are fixed hand-wheels a^5 by which it may be turned; and bevel-pinions a^4 , a^4 , are secured on the shaft near the bearing blocks a^1 , a^1 . In horizontal projections from the frame extensions a^2 , are 80 journaled vertical screw shafts a^6 on the upper ends of which are fixed beveled pinions a^7 , a^7 , which mesh with the pinions a^4 , a^4 . Below their journals, the shafts a^6 are shouldered and threaded and engage threaded 85 openings in lugs h^1 which project from the face of the tool-carrying frame to be described. The turning of the hand-wheels a^5 , will adjust the tool carrying frame vertically, through the engagement of pinions a^4 , a^7 , and 90 the shafts a^6 , with the threaded lugs h^1 .

The tool-carrying frame is composed of two brackets H , H , which extend at right-angles from the upper part of the bed of the machine, and of upper and lower rear cross-bars h^2 , h^2 , and lower front cross-bars h^3 all suitably secured together to form a rigid structure. From the outer edge of each of the brackets H projects a flange h^5 in which vertical slots h^6 are formed. Slidably fitting 100 the slots h^6 are bolts h^8 which have threaded 105 engagements with openings in the vertical side members of the machine bed, said bolts serving to limit the tool carrying frame in its vertical adjustments. On the rear side of 110

each of the vertical members h^5 projects a tongue h^{10} which slidably engages a groove a^8 in the outer face of the vertical members of the bed A, said tongues and grooves serving as vertical guides and slideways for the tool carrying frame. (See Fig. 6.) At a point half-way between the brackets H, H, an arm h^4 is bolted to, and extends at right angles from, the bars h^2 , and same serves as a support for the tracer and the means for driving same and the main drive-pulleys for the carving tools. In the arm h^4 is vertically journaled a shaft k on the upper portion of which is fixed a main drive pulley k^3 which may be belted to and driven by any suitable power. The shaft k extends through a cut out portion h^9 of the arm and at this point has fixed thereon two pulleys k^1 and a smaller pulley k^2 all grooved to receive round belts k^6 and k^7 respectively. In the outer end of the arm h^4 is journaled a suitable socket for a tracer tool k^5 which is driven by a grooved pulley k^4 which in turn is driven by the belt k^7 from the pulley k^2 . A similar socket k^{10} is provided about midway the arm in case it should be desired to attach a tracer at that point.

On the outer end of each of the brackets H, H, is journaled a socket k^9 adapted to carry a cutting or carving tool k^8 , said socket being driven by one of the belts k^6 running from the respective pulleys k^1 and around the pulleys k^4 . The tool sockets are of the usual construction in such machines and need not be particularly described.

Projecting at right angles from the lower part of the bed of the machine are two brackets B, B, which serve as supports for the work and pattern carrying elements to be described. Secured rigidly to the upper side of the brackets B, are two transverse rails b^1 , b^1 , which are placed at the outer end and near the center of the brackets, respectively. The ends of the rails are bent to form stops b^2 . Slidably mounted on each of the rails b^1 , are two blocks C each of which is constructed and arranged (see Figs. 4 and 10) as follows:—The block in cross-section is in the shape of a channel-bar and is arranged with the flanges extending upwardly. Two stud bolts are tapped into the under side of the block, on each of which is mounted a roller c^1 , said rollers being so arranged as to frictionally embrace opposite sides of the head of the rail b^1 . Bolted to the upper side of the block are plates c^4 , c^4 , and in the adjacent faces of the block and plate are cut registering longitudinal grooves which form a journal and race-way c^3 for the spindles of the roller c^2 the latter being so arranged and of such diameter as to have its face engage the upper face of the head of the rail b^1 .

There are four blocks C employed in our machine, which serve as carriers or trucks for two rails D, D, which are arranged trans-

versely to the rails b^1 , and together with the front and rear rods D^1 , D^1 , which connect the ends of said rails, form a frame which is adapted to slide from right to left on the rails b^1 , b^1 . The rails D are of the same shape in cross-section as the rails b^1 and have their ends turned up to form stops d^2 . Mounted on the rails D are four blocks D^3 which are of the same construction and operation as the blocks C above described. Coupled to the carriers D^3 are two side bars E, and front and rear bars E^1 , E^1 , the same being preferably made of tubes and together with said carriers, form a rectangular frame with a carrier at each of its four corners.

Bolted to each of the carriers D^3 is a standard F, in the upper end of which is journaled the spindle of a hanger J which is adapted to swing freely in its bearings. To the lower ends of the four hangers J, is pivotally connected a frame composed of two side tubular bars G, G, and front and rear tubular bars G^1 , G^1 , suitably coupled together. Extending transversely of this frame, about midway between the front and rear bars, a middle bar G^2 is coupled to the side bars G, and carries couplings M^1 which permit of longitudinal adjustment on said bars G. Supported from the couplings M^1 are clamping screws m^3 which serve as adjustable supports for one end of the pattern, and the pieces being carved. The opposite end of said pattern and pieces is held by chucks m^4 which are of the usual style and are suitably connected with the couplings M. Any other means of clamping the pattern and work pieces may be substituted for those shown.

From the foregoing description, it will be apparent that the blocks D³ and their connected bars and standards will slide freely backwards and forwards on the rails D, such movements being at right angles to the movements of the blocks C and connected rails D, D¹. It will also be plain that the frame formed by the coupled bars G, G¹ and G² will be swingingly supported on the standards F thus permitting the movement of the work pieces and the pattern in corresponding planes.

Adjustably secured on the side bars E, E, are sleeves e^1 , e^1 , on each of which is secured by a stud bolt e^6 a bracket e^2 through which a slot e^3 is formed. Arranged in the slot e^3 is an upwardly curved flat metal spring e^4 in the upper end of which is journaled a roller e^8 the face of which is concave to adapt it to fit the bar G against the under side of which the roller bears. Set screws e^5 extend through vertical threaded openings in the upper portion of the brackets and when screwed down against the spring e^4 hold it in its adjusted position, relative to the bracket. To adjust the bracket e^2 on its bolt e^6 so as to bring the free end of the spring e^4 with

greater or less tension against the bar G, we provide a set screw e⁷ which passes through a threaded opening in the bracket at one side of the axis of the latter and has its lower 5 end impinge against the sleeve e¹, as clearly shown in Figs. 8 and 9. In practice the springs e⁴ will be so adjusted as to counter-balance in part the weight of the pattern and work pieces, and their supporting frame composed of the bars G, G¹ and G², so that but slight muscular effort will be required on the 10 part of the operator in moving the work back and forth and up and down within the limits permitted by the rocking or swinging 15 frame.

Having thus described our invention what we claim as new and desire to obtain by Letters Patent, is:—

1. In a carving machine, a vertically arranged bed adapted to be secured to a wall, brackets rigidly secured to the bed and extending at right angles therefrom, rails fixed on said brackets, rails slidably mounted on and at right angles to said fixed rails, a work 25 and pattern - carrying frame adjustably mounted on said slide rails, a tracer and cutting tools and means for supporting and means for driving same.

2. In a carving machine, a vertically arranged bed adapted to be secured to a wall, brackets rigidly attached to and extending at right angles from said bed, rails arranged transversely of, and rigidly attached to, said brackets, carriers or trucks mounted on said 35 rails and having roller bearings engaging said rails, other rails secured to said carriers slideable therewith, and arranged transversely of said fixed rails, a frame slidably mounted on said slide rails, a frame swingingly supported on said slide frame, means for supporting a pattern and work on said swinging frame, a tracer and cutting tools and means respectively for supporting and driving same.

45 3. In a carving machine, a vertical supporting bed, a horizontal tool-carrying frame vertically adjustable on said bed, tool holders rotatably mounted on said frame, means for driving said holders, said means carried by 50 said frame, a work-carrying frame arranged and suitably supported below said tool-carrying frame, and means whereby said work-carrying frame may be moved in straight and on curved lines.

4. In a carving machine, a vertical supporting bed, a horizontal tool-carrying frame vertically adjustable on said bed, tool holders rotatably mounted on said frame, means for driving said holders, work-carrying means arranged below said tool-carrying frame, and 60 consisting of two slideable frames adapted to move on intersecting horizontal lines, and a frame swingingly supported on one end of said slideable frames.

5. In a carving machine, a vertical supporting bed, a horizontal tool-carrying frame vertically adjustable on said bed, tool holders rotatably mounted on said frame, means for driving said holders, said means carried by 65 said frame, work-carrying means arranged below said tool-carrying frame and consisting of two slideable frames adapted to move in horizontal intersecting lines, and a frame swingingly and yieldingly supported on said frames.

75 6. In a carving machine, work and pattern carrying means consisting of two frames mounted to slide in intersecting horizontal lines, a swinging frame supported on one of the slideable frames, and work holding devices adjustably arranged on said swinging frame.

80 7. In a carving machine, work and pattern carrying means consisting of two frames mounted to slide in intersecting horizontal 85 lines, a swinging frame supported on one of the slideable frames, work holding devices arranged on said swinging frame, and adjustable means for yieldingly supporting said swinging frame.

90 8. In a carving machine, a vertical supporting frame, rails fixed on said frame, rails arranged transversely of and slideably mounted on said fixed rails, other rails arranged transversely of and slideably mounted 95 on said last named rails, anti-frictional bearings for both sets of slide rails, and a work and pattern supporting frame swingingly mounted on said supporting frame substantially in the manner set forth.

100 In testimony whereof we affix our signatures in presence of two witnesses.

JOSEPH SCHMITT.
